UNITED STATES PATENT OFFICE.

ALEXANDER VOSMAER, OF HAARLEM, NETHERLANDS, ASSIGNOR TO COMPANY OZON MAATSCHAPPI SYSTEEM A. VOSMAER, OF AMSTERDAM, NETHERLANDS.

OZONIZING APPARATUS.

SPECIFICATION forming part of Letters Patent No. 709,427, dated September 16, 1902.

Application filed October 4, 1901. Serial No. 77,545. (No model.)

To all whom it may concern:

Be it known that I, ALEXANDER VOSMAER, a subject of the Queen of the Netherlands, residing at 49 Zylweg, Haarlem, in the Kingdom of the Netherlands, have invented certain new and useful Improvements in Ozonizing Apparatus, of which the following is a specification.

My invention relates to an ozonizing apparatus of simple construction in which the electrodes are completely independent of the casing of the apparatus in which circulates the air, for example, to be ozonized and from which they can be easily removed and replaced when necessity arises and adjusted with relation to each other.

To this end my invention consists, essentially, in the employment of two separate electrodes, one of which (the discharger) consists of a suitable support provided with pins or points arranged side by side, as described in my former patent, No. 636,304, while the other consists of a bar of suitable metal and section completely independent of the rest of the apparatus and supporting the discharger by means of insulated supports, the whole arrangement of the two electrodes thus formed being afterward placed loosely in a tube of convenient diameter (or in a suitable casing) arranged horizontally, so that the bar of metal resting in the said tube may support the discharger vertically therein without necessitating any means of attachment to the side of the said tube.

In the annexed drawings, Figure 1 is a sectional longitudinal view of a part or element of an apparatus constructed according to my invention. Fig. 2 is a section taken on line A A, Fig. 1. Fig. 3 is a top view of the electrodes. Fig. 4 is a section similar to Fig. 2 of a modification of the apparatus. Fig. 5 is a top view of an apparatus comprising a number of elements similar to those of Fig. 1.

The horizontal tubes 1 may, for example, be ordinary gas-pipes. In each of these tubes 1 are placed the electrodes, of any suitable metal, comprising a metal bar 2 of square or rectangular section, in which are fixed at intervals supports 3 of insulating material—porcelain, for example—having at their up-

per part a fork 4, in which rests a rod 5, provided with the pins or points 6 and constituting the discharger. The metal bar 2 consequently serves as a base for the discharger 5, and it is only necessary to introduce this bar 2, carrying the discharger 5, into the horizontal tube 1 in order to form one of the elements of the apparatus. The current of air to be ozonized enters at one of the ends of the tube 1 and passes out through the other, consequently circulating in the plane wherein the electric discharges take place.

It is obvious that the apparatus may comprise a number of similar tubes 1, united, for example, at their ends by inlet and outlet cases 7 for the air. Such an apparatus is shown, for example, in Fig. 5. An apparatus of considerable power can thus be easily constructed of very small size by arranging the whole of the tubes 1 side by side in a similar manner to the arrangements generally adopted for the construction of steam surface condensers. Each element may also comprise a certain number of electrodes 2 and 5, arranged parallel with each other in a tube or casing 1 of convenient size, as shown in Fig. 4.

The advantages of an apparatus constructed according to the hereinbefore-described improvements will be readily understood.

The use of the bar 2, of metal, supporting the discharger 5 through the medium of the insulated supports 3, renders the arrangement of the electrodes easily removable from and completely independent of the tubes of the apparatus, contrary to what has been the case in all apparatuses hitherto in use. An important advantage results therefrom as regards the replacing of the dischargers 5, this replacement no longer requiring, as was formerly the case, the removal or the putting out of use of the tubes of the apparatus. Moreover, the distance separating the electrodes can be regulated without any difficulty by simply filling up the forks with loose pieces of plate or using different sizes of pillars for said forks.

In the example hereinbefore described I have supposed the tubes to be simple drawn tubes, like ordinary gas-pipes, and I prefer

these tubes because they are inexpensive. In this case the tubes form, with the metal bar, a part of one of the electrodes of the apparatus, the metal bar being not insulated in the tube.

I would observe that one of the essential characteristics of the apparatus hereinbefore described resides in the horizontal arrangement of the tubes and the electrodes. This arrangement is indispensable for allowing the metal bar to support the discharger and to create complete independence between the electrodes and the tube or receiver which surrounds them.

15. What I claim is—

1. In an ozonizing apparatus, the combination of metal bars of suitable section, insulating-supports fixed on the said bars, metal rods supported by the said insulating-supports and having depending points and a horizontally-arranged casing, each metal bar with its insulating-supports and the metal

rod carried by the said supports forming a single structure which is loosely placed in the casing, substantially as described and for the purpose set forth.

2. In an ozonizing apparatus in combination metal bars of suitable section, insulating-supports fixed at intervals in the said bars and being provided with a fork at their upper part, rods with points resting in the forks of the insulating-supports and horizontally-arranged casings in which the metal bars supporting the rods with points through the insulating-supports, are loosely placed substantially as described and for the purpose set forth.

In witness whereof I have hereunto set my hand in presence of two witnesses.

ALEXANDER VOSMAER.
